UNITED STATES PATENT OFFICE.

VASILE CONSTANTINESCU, OF NELSON, BRITISH COLUMBIA, CANADA.

COMBINED CALIPERS AND PROTRACTOR.

1,039,901.

Specification of Letters Patent.

Patented Oct. 1, 1912.

Application filed March 5, 1912. Serial No. 681,780.

To all whom it may concern:

Be it known that I, VASILE CONSTANTINESCU, a citizen of the Dominion of Canada, residing at Nelson, in the Province of British Columbia and Dominion of Canada, have invented certain new and useful improvements in Combined Calipers and Protractors, of which the following is a specification.

10 The present invention relates to a combined registering caliper and protractor, for use in measuring the interior and exterior of cylindrical and tapered work.

15 An important object of my invention is to provide a device of the above mentioned character, having means for ascertaining the taper of a piece of work in inches or the like per foot.

20 A further object of my invention is to provide means of the above mentioned character, which may be quickly adjusted to the work and will give accurate figures or readings.

25 A further object of my invention is to provide means of the above mentioned character, which are simple in construction, easy to operate, and cheap to manufacture.

30 Other objects and advantages of the invention will be apparent during the course of the following description.

In the accompanying drawings forming a part of this specification and in which like numerals are employed to designate like parts throughout the same, Figure 1 is a 35 plan view of the device, showing it applied to a piece of tapered work, Fig. 2 is a sectional view taken on line 2—2 of Fig. 1 and looking in the direction of the arrows, Fig. 3 is a longitudinal sectional view taken on line 3—3 of Fig. 1 and looking in the direction of the arrow, Fig. 4 is a detail sectional view taken on line 4—4 of Fig. 1, Fig. 5 is a similar view taken on line 5—5 of Fig. 1, Fig. 6 is a fragmentary view of 45 one end of the protractor, showing the protractor leg reversed, and, Fig. 7 is an enlarged fragmentary plan view of a calculating scale.

50 In the drawings wherein for the sake of illustration, I have shown a preferred em-

bodiment of my invention, the numeral 1 designates the body portion or base of the protractor, comprising a sector or protractor plate 2, having the usual degree graduations 3 formed thereon, as shown.

55 The numeral 4 designates a caliper blade, provided with a scale 5 laid out in inches and fractions thereof. This caliper blade 4 has one end thereof pivotally connected with the base 1 of the protractor, by means of a screw 6 or the like. The sector plate 2 is provided with a curved slot 7, for receiving a clamping screw 8, carried by the caliper blade 4, as shown. By the manipulation of this clamping screw 8 the caliper blade 4 60 may be securely locked in adjustment at different angular positions with relation to the sector or protractor plate 2.

65 The protractor blade 4 has a curved calculating plate 9, rigidly connected therewith by means of screws 10 or the like. This plate 9 is disposed adjacent the sector plate 2 and is provided with a scale 11, graduated in inches and fractions thereof, as shown. This scale has a central zero mark and the 70 graduations increase to the right and left of the same, as shown. The zero mark of the scale 11 is adapted to normally coincide with the ninety degree mark of the scale 3. The graduations of the scale 11 are 75 designated by numerals or calculations 12, which indicate the rise in inches per foot of the work having the angle of taper as ascertained on the scale 3. Attention is called to the fact that the graduations of the scale 80 11 are adapted to coincide with those of the scale 3.

75 Slidably mounted upon the caliper blade 4 is a transverse carriage 13, having an opening 14 formed therethrough for receiving this blade. The carriage 13 is provided with a clamping screw 15, having its inner end operating in a slot 16 formed upon the upper face of the caliper blade 4 and extending longitudinally thereof. The carriage 13 85 is provided upon its inner face and midway its ends with a beveled portion 17, to cooperate with the scale 5. In order that the carriage 13 may not move too freely longitudinally of the blade 4, I provide such car- 90 95 100

riage with an opening or recess 18 within which is disposed a bow-spring 19, having frictional engagement with one longitudinal edge of the blade 4. Slidably mounted upon 5 the caliper blade 4 is an adjusting carriage 20, carrying a clamping screw 21, which engages a bow-spring 22, interposed between the end of the carriage 20 and the edge of the caliper blade 4. The spring 22 prevents 10 the carriage 20 from being moved too freely longitudinally of the blade 4 and the screw 21 may be manipulated to clamp or lock the adjusting carriage 20 to the caliper blade 4. Pivotally connected with the transverse or 15 main carriage 13 is a screw 23, as shown at 24. This screw passes through a suitably large opening in the free end of the adjusting carriage 20. An adjusting nut 25 is carried by the screw 23 and operates within an 20 opening formed in the carriage 20. A spring 26 surrounds the screw 23 and is interposed between the adjusting carriage 20 and the transverse carriage 13 to take up any loose motion between these carriages.

25 The base 1 of the protractor carries at its ends depending caliper legs 27, which are preferably curved longitudinally, as shown. The caliper legs 27 have heads or carriages 28 formed upon their upper ends, which 30 slidably engage the under surface of the base 1. These carriages 28 are provided with upstanding screws 29, extending through a longitudinal slot 30, which is formed through the base 1. The screws 29 35 carry thumb or clamping nuts 31, which engage the upper face of the base 1 and are adapted to securely lock the caliper legs 27 in adjustment at different positions upon the base 1. The carriages 28 are provided with 40 upstanding flanges or guides 32, adapted to slidably engage the outer longitudinal edge of the base 1. When the device is used for measuring the exterior of work, the caliper legs 27 extend inwardly. When it is de- 45 sired to measure the interior of work, these caliper legs must be arranged to extend outwardly. This is accomplished by interchanging the caliper legs 27. When this is done the flanges or guides 32 will be dis- 50 posed to operate within longitudinal slots 33. It is thus seen that the caliper legs 27 are adjustable so as to measure the exterior and interior of work and may also be ad- 55 justed longitudinally of the base 1 toward and away from each other, depending upon the length of the piece of work which is to be measured.

60 The main or transverse carriage 13 carries at its ends depending caliper legs 34, which are curved longitudinally and of the same shape as the oppositely arranged caliper legs 27. The caliper legs 34 have heads or carriages 35 formed upon their upper ends, which are provided with upstanding

flanges or guides 36, having slideable engagement with the longitudinal edges of the carriage 13. The carriage or heads 35 carry upstanding screws 37, operating through longitudinal slots 38, and provided above the carriage 13 with thumb or clamping 65 nuts 39. The upper and lower caliper legs 34 may be readily interchanged so that they may extend outwardly instead of inwardly, for the reason as stated in connection with the caliper legs 27.

75 The operation of the device is as follows: When the device is used as a caliper for measuring the exterior of cylindrical work, the main carriage 13 is properly adjusted so that the work may be placed between the 80 pairs of caliper legs 27 and 34. The zero mark of the scale 11 now coincides with the ninety degree mark of the scale 3, whereby the base 1 is arranged at right angles to the caliper blade 4. The screw 21 is clamped 85 to the blade 4 for holding the carriage 20 against movement, subsequently to which the adjusting nut 25 is turned to effect a fine adjustment of the carriage 13. It is thus seen that the diameter of the work will be 90 indicated by the portion 17 on the scale 5.

When it is desired to measure a tapered piece of work the pairs of caliper legs 27 and 34 are moved sufficiently far apart to permit of the tapered work being placed therebetween. The clamping nut or screw 8 is now turned to permit of the caliper blade 4 being swung to assume the desired angular position with relation to the base 1, which of course depends upon the angle of taper 95 of the work. The caliper legs 27 and 34 are now moved into engagement with the piece of tapered work and the clamping screw 8 turned to securely hold the blade 4 in its adjusted position. The fine adjustment of the 100 carriage 13 may be had by the manipulation of the carriage 20 and its adjusting nut 25, as hereinabove described. The carriage 13 may be securely clamped in its adjusted position by turning the clamping screw 15. 110 As shown in Fig. 1, the device is applied to a piece of tapered work. The zero mark of the scale 11 is now thirteen degrees from the ninety degree mark of the scale 3, indicating 115 on the scale 3 that the angle of taper is thirteen degrees. The ninety degree mark of the scale 3 now points to the graduation on the scale 11, which is designated by two and one-hundred-nine one-hundred-and-sixtieths (see Fig. 7) which indicates the rise in 120 inches per foot of the work having an angle of taper of thirteen degrees.

125 Suppose that it is known that the desired piece of work is to have an angle of taper of thirteen degrees. The blade 4 is then ad- justed to assume the position shown in Fig. 1, whereby it will be found that the rise in inches per foot is two and one-hundred-nine

one-hundred-and-sixtieths. The length of the piece of work is measured and the operating parts of the lathe are accordingly adjusted to correspond with this rise in inches 5 per foot.

The device may be used to measure short work which is accomplished by bringing the caliper legs in each pair closer together and clamping them in their adjusted positions.

10 The device may be readily employed as an interior caliper for measuring cylindrical and tapered grooves. When this is to be done the caliper legs in each pair are interchanged so that they will extend outwardly 15 instead of inwardly. The operation then proceeds in a similar manner as has been stated.

It is to be understood that the form of my invention herewith shown and described is 20 to be taken as a preferred example of the same and that certain changes in the shape, size, and arrangement of parts may be resorted to without departing from the spirit of the invention or the scope of the subjoined claims.

25 Having thus described my invention, I claim:—

1. In a device of the character described, a caliper comprising a base plate and sector 30 provided with a scale, caliper legs longitudinally adjustably mounted upon said base plate, a caliper blade pivotally connected with the base plate, means to clamp the caliper blade to the protractor in adjustment 35 at different angular positions, a carriage longitudinally movably mounted upon the caliper blade, and caliper legs longitudinally adjustably mounted upon the carriage.

2. In a device of the character described, a 40 protractor comprising a sector having a scale, a set of caliper legs carried by the protractor, means whereby the caliper legs in this set may be adjusted and interchanged, a caliper blade pivotally connected with said 45 protractor and provided with a scale, a graduated calculating plate connected with the caliper blade and operating adjacent said sector and having its graduations designated by numerals indicating the rise in 50 inches per foot of the work for a given angle ascertained on the sector scale, a carriage longitudinally movably mounted on the caliper blade, caliper legs connected with the carriage, and means whereby such caliper legs may be adjusted and interchanged.

3. In a device of the character described, a protractor plate provided with a scale, interchangeable caliper legs removably mounted upon the protractor plate, a caliper blade 60 pivotally connected with the protractor plate and provided with a scale, a carriage mounted upon the caliper blade to be moved longitudinally thereof, and interchangeable caliper legs connected with the carriage.

4. In a device of the character described, 65 a protractor plate provided with a scale, caliper legs adjustably mounted upon the protractor plate to be moved toward and away from each other, a caliper blade pivotally connected with the protractor plate and 70 provided with a scale, a carriage adjustably mounted upon the caliper blade to be moved longitudinally thereof, and caliper legs adjustably mounted upon the carriage to be moved thereon toward and away from each 75 other.

5. In a device of the character described, a protractor plate provided with a scale, curved caliper legs removably mounted upon the protractor plate and adapted to be interchanged, a caliper blade pivotally connected with the protractor plate and provided with a scale, a carriage adjustably mounted upon the caliper blade to be moved longitudinally 80 of the same, and curved caliper legs removably mounted upon the carriage and adapted to be interchanged.

6. In a device of the character described, a protractor plate provided with a scale, caliper legs connected with the protractor 90 plate near the ends thereof, a caliper blade pivotally connected with the protractor plate between said caliper legs, said caliper blade being provided with a scale, a carriage mounted upon the caliper blade to be 95 moved longitudinally thereof, and caliper legs connected with the carriage near the ends thereof.

7. In a device of the character described, a protractor plate including base and sector 100 portions, the sector portion being provided with a scale, caliper legs connected with the base portion near the ends thereof, a caliper blade pivotally connected with the base portion between said caliper legs, a clamping 105 device connected with the caliper blade and engaging the sector portion, a carriage extending transversely of the caliper blade and adapted to be moved longitudinally of the same, and caliper legs connected with the 110 end portions of the carriage.

8. In a device of the character described, a protractor plate including base and sector portions, the sector portion being provided with a scale and a longitudinal slot, caliper 115 legs connected with the base portion near the ends thereof, a caliper blade pivotally connected with the base portion between said caliper legs, a clamping device connected with the caliper blade and operating 120 within the longitudinal slot of the sector portion, a sector provided with a scale and rigidly connected with the caliper blade to operate adjacent the sector portion, a carriage extending transversely of the caliper 125 blade, and caliper legs connected with the carriage.

9. In a device of the character described,

a plate, caliper legs connected therewith near the ends thereof, a caliper blade pivotally connected with the plate between the caliper legs, means for defining the angle at 5 which the caliper blade is set with relation to the said plate, a carriage movably mounted upon the caliper blade, and caliper legs connected with the carriage near the ends

thereof to be disposed in opposition to the first named caliper legs.

In testimony whereof I affix my signature in presence of two witnesses.

VASILE CONSTANTINESCU.
